US00D767672S

(12) **United States Design Patent** (10) Patent No.: **US D767,672 S**
(45) Date of Patent: ** Sep. 27, 2016

(54) **INK TANK FOR PRINTER**

- (71) Applicant: **Canon Kabushiki Kaisha**, Ohta-ku, Tokyo (JP)
- (72) Inventors: **Tatsuo Nanjo**, Kawasaki (JP); **Yasuo Kotaki**, Yokohama (JP); **Kenta Udagawa**, Tokyo (JP); **Hiroshi Koshikawa**, Yokohama (JP); **Wataru Takahashi**, Yokohama (JP); **Koichi Kubo**, Yokohama (JP); **Shigeki Fukui**, Kawasaki (JP); **Naozumi Nabeshima**, Tokyo (JP); **Soji Kondo**, Yokohama (JP); **Masafumi Seki**, Kawasaki (JP); **Kazuya Yoshii**, Yokohama (JP); **Yasunori Senshiki**, Tachikawa (JP)
- (73) Assignee: **CANON KABUSHIKI KAISHA**, Tokyo (JP)
- (**) Term: **14 Years**
- (21) Appl. No.: **29/504,234**
- (22) Filed: **Oct. 3, 2014**

(30) **Foreign Application Priority Data**

- Apr. 4, 2014 (JP) 2014-007414
- (51) LOC (10) Cl. **18-02**
- (52) U.S. Cl. **USPC** **D18/56**
- (58) **Field of Classification Search**

(57) **CLAIM**

The ornamental design for an ink tank for printer, as shown and described.

DESCRIPTION

FIG. 1 is a front view of an ink tank for printer showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a rear, bottom and right side perspective view thereof; and,

FIG. 8 is a front, top and left side perspective view thereof. The broken lines depict environmental subject matter only and form no part of the claimed design.

1 Claim, 6 Drawing Sheets
